UNITED STATES PATENT OFFICE.

CHARLES WESLEY HOWELL, JR., OF NEWARK, NEW JERSEY, ASSIGNEE TO THE SUN
TYPEWRITER COMPANY, OF NEW YORK, N. Y., A CORPORATION OF NEW JERSEY.

PRINTING.

1,130,404.

Specification of Letters Patent.

Patented Mar. 2, 1915.

Application filed May 25, 1911. Serial No. 629,361.

To all whom it may concern:

Be it known that I, CHARLES WESLEY HOWELL, Jr., a citizen of the United States, residing at Newark, in the county of Essex 5 and State of New Jersey, have invented certain new and useful Improvements in Printing, of which the following is a specification, reference being had therein to the accompanying drawing.

10 My invention relates to improvements in printing and has particular reference to the printing done on a writing machine such as a typewriter.

One of the principal objects of my invention is to produce printing which cannot be changed, altered, or erased without detection and to this end I prefer to employ pin pointed type. I also prefer to use a specially prepared base or back for this work 20 and have found that the best results are obtained by using a yielding and non-elastic material such as wax mixed with suitable indelible coloring material.

In the accompanying drawings I have 25 illustrated in Figure 1 in cross section one application of my invention showing the position of the penetrating pin points of the type through the paper and its backing upon the roller of the machine. Fig. 2 is a front 30 view of a piece of pin pointed type such as I prefer to use, and Fig. 3 is a side view looking from right to left at Fig. 2.

My invention is particularly adapted for use in making out checks owing to the fact 35 that checks are often raised in amount after they have been issued. For this purpose it is best to select a typewriter which is provided with pin pointed type although other kinds of type may be used. When type other than 40 pin pointed type is used, the lines of the letters made by the type are not perforated and it is by means of the perforations made by the pin pointed type that alteration, erasure or changing of the printing is made practically impossible without detection. It is 45 also preferable to use a machine such as the Sun typewriter in which the type is inked by an inking roller mechanism instead of by an inking ribbon. It would require 50 very heavy striking to force the points of pin pointed type through an inking ribbon and then only the points would print, whereas by using a ribbonless machine or a machine having an inking roller mechanism 55 an entire outline of each letter is printed

over the perforations. The best results have been obtained by mixing lithographer's ink or other suitable indelible coloring material with the wax but the mixture should retain as near as possible the same consistency as 60 wax and it should be prepared in sheets.

In carrying out my invention according to my preferred method of procedure I introduce into a ribbonless typewriter with pin pointed type, the blank form of a check, 65 such as 4, and a blank piece of paper of the same size, such as 5, for a duplicate record and between these two blanks I also introduce the sheet backing or base of wax (which may be double faced) with the indelible coloring matter, such as 6. During 70 the printing operation the points 7 of the type should pass entirely through the check and the wax and should be in length about equal to the thickness of the check and the 75 wax so that the outline of the letter 8 of the type from which the points project are printed upon the face of the check between the perforations made by the points. The 80 printing on the check is also reproduced in dotted outline by the points of the type upon the blank piece of paper intended for the duplicate record. The slight heat generated by the impact of the type is sufficient to melt small portions of the colored wax which 85 wipe off the points as the type leaves the paper and deposit on the inside of the perforations of the check where they penetrate and saturate the fibers of the paper of the 90 check and become thoroughly hardened. The back of the check will of course disclose a negative of the indelibly stained perforated printing, and the hardened wax in the fibers extending within the perforations of 95 the check will be found to be practically acid proof and sufficiently inaccessible to be unaffected by rubbing or scratching.

A result can be obtained by placing a piece of double faced transfer paper between two blanks providing a piece of well 100 waxed thin and strong paper is placed behind the blank which is intended for a duplicate. Transfer paper alone will not give proper results as it is made so thin for duplicating purposes that it has not sufficient 105 body and there is too much fiber in proportion to the amount of wax. This excess of fiber destroys the characteristic yielding quality of the wax which is essential to prevent embossing, a condition very ob- 110

jectionable to the banks. A sufficient quantity of wax for the type to strike against, however, enables the points to travel the necessary depth to allow the lines of the type to print between the perforations in the check. If the wax sheet is not sufficiently thick or if it is omitted, only the points of the type will print so that the printing will be in dotted outline.

10 It has been found that the wax and coloring material hold better in the perforations when the wax and coloring material are mixed and formed in sheets than when transfer paper and a wax sheet are used. Very 15 good results have been obtained by forming wax and indelible pigment into sheets approximately five or six times the thickness of ordinary carbon paper.

Of course it will be understood that other 20 modifications can be made without departing from the spirit of the invention as set forth in the claims.

I claim:

1. The method of printing consisting in 25 separating the sheets to be printed by a double faced, yielding and non-elastic trans-

fer sheet, and printing through one of said sheets to be printed by means of pin pointed type and through said transfer sheet upon the other of said sheets substantially as described.

2. The method of printing with penetrating type consisting in backing the sheet to be printed with a colored yielding and non-elastic body, said backing and sheet of 35 an aggregate thickness about equal to the length of the penetrating portions of said type.

3. The method of printing with penetrating type consisting in separating the sheet to be printed by a sheet of colored yielding and non-elastic material, one of said sheet and said material of an aggregate thickness about equal to the length of the penetrating portion of said type.

In testimony whereof I affix my signature in presence of two witnesses.

CHARLES WESLEY HOWELL, JUNIOR.
